APPARATUS FOR TREATING TEXTILE FILAMENTS

Heinz Eggink, Wuppertal-Elberfeld, Hugo Elling, Franz Ettinger, and Karl Ostertag, Oberbruch-Grebben, and Kurt-Jurgen Schulze, Oberbruch, Germany, assignors, by mesne assignments, to American Enka Corporation, Enka, N. C., a corporation of Delaware

Application February 16, 1953, Serial No. 337,145

Claims priority, application Germany February 14, 1952

12 Claims. (Cl. 68—175)

The present invention relates to an apparatus for processing textiles.

More particularly, the present invention relates to an apparatus for processing filaments, such as those formed from synthetic materials.

Newly spun filaments of the above type must be processed just after the spinning thereof by being passed through several baths of treating liquids of different types. These filaments are usually guided in groups through the baths, and the movement of the filaments through the bath liquid creates a turbulence in the latter which produces an undesirable bending of the filaments and at the same time a spreading of the same so that short filament portions extend laterally from the filaments. It has been found that sometimes the bending of the filaments may be as much as 30 mm., and the spreading of the fibers produces an undesirable clinging of the filaments to each other. Also, the bending of the filaments is particularly undesirable since it very often causes the filaments to slip from the guide rolls.

One of the objects of the present invention is to overcome the above disadvantages by providing an apparatus which prevents the creation of a turbulence in the bath liquid through which a group of filaments passes.

A further object of the present invention is to provide an apparatus, for preventing turbulence, which is of an extremely simple and rugged construction.

With the above objects in view, the present invention consists of an apparatus for treating textile filaments, this apparatus including a bath and a pair of spaced guide rolls associated with the bath for guiding a group of filaments therethrough. A pair of opposite elongated plates are spaced from each other, located between the rolls, and are arranged along a path extending from one of the rolls to the other of the rolls so that when a group of filaments are guided between the plates the latter will prevent a turbulence in the bath liquid between the plates and will thereby prevent bending and spreading of the filaments. Also, a floor portion extends between the plates and is connected to the lower edges thereof to prevent a turbulence in the liquid at the underside of the group of filaments passing through the bath.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a diagrammatic top plan view of a known treating bath and illustrates the turbulence of a liquid therein;

Fig. 2 is a diagrammatic side elevational view of an apparatus constructed in accordance with the present invention;

Fig. 3 is a partly diagrammatic top plan view of the structure of Fig. 2;

2

Fig. 4 is a diagrammatic side elevational view of another embodiment of the invention;

Fig. 5 is a diagrammatic transverse view of a further embodiment of the invention;

Fig. 5a is a partial diagrammatic side elevational view of the embodiment shown in Fig. 5;

Fig. 6 is a transverse diagrammatic view of a variation of the structure of Fig. 5;

Fig. 7 is a diagrammatic side elevational of still another embodiment of the present invention; and

Fig. 8 is a top plan view of a further variation of the structure of the present invention.

Referring now to the drawings, a conventional treating bath is shown in Fig. 1 where the guide rolls 1 and 2 are associated with the bath for guiding a group of filaments therethrough in the direction shown by the arrow at the lower part of Fig. 1. The filaments produce a turbulence in the liquid of the bath which causes the bath liquid to circulate in the direction of the dotted lines 3 and arrows thereon shown in Fig. 1. As was mentioned above, this turbulence is very undesirable because it produces undesirable bends in the filaments and furthermore causes the filament fibers to spread so that short fine filament portions extend from the filaments and cause the latter to undesirably cling to each other.

Figs. 2 and 3 show one possible construction for overcoming the disadvantages of the conventional structure illustrated in Fig. 1. As is shown in Figs. 2 and 3, a pair of plates 4 are arranged in the bath 14 in spaced relation to each other and extending between the guide rolls 1 and 2 which guide the filaments to the left, as viewed in Figs. 2 and 3, the roll 1 being an entrance roll for introducing the filaments to the bath and the roll 2 being a discharge roll for discharging the filaments from the bath. The plates 4 are located fairly close to the rolls 1 and 2 which guide the filaments and extend above the level 5 of the liquid in the bath, and these plates 4 effectively prevent a turbulence of the type shown in Fig. 1. The plates 4 are interconnected by a floor member 7 which extends between the plates 4 and is connected to the bottom edges thereof, this floor member 7 being located close to the underside of the group of filaments so as to prevent any turbulence in the bath liquid at the underside of the group of filaments passing through the bath.

It is possible to mount the trough-shaped structure 4, 7 in any suitable way in the bath so that it is located in the position shown in Figs. 2 and 3, and Fig. 3 illustrates one possible supporting structure which includes the straps 11 fixed to and extending from the plates 4 and engaging opposite edges of the bath so as to maintain the structure 4, 7 in the position shown.

Fig. 4 illustrates a variation of the structure of the invention according to which the floor part 7' is inclined so that its right end, as viewed in Fig. 4, is more distant from the entrance roll 1 than its left end is distant from the discharge roll 2, and thus the floor 7' gradually approaches the filaments as they proceed through the bath to very effectively prevent turbulence at the discharge roll 2. Moreover, the side walls 4' of the embodiment of Fig. 4 are each formed at their opposite ends with cutouts 12 into which the rolls 1 and 2 respectively extend, so that turbulence of the bath liquid is effectively eliminated even at the region of the rolls 1 and 2.

Figs. 5 and 5a illustrate a variation according to which the discharge roll 2' is formed with annular grooves 13, respectively adjacent its opposite ends, and the trough-shaped structure 4'', 7 extends into these grooves to reduce turbulence in the region of the discharge roll 2 in this way.

Fig. 6 illustrates a further variation according to which

the side plates 9 extend to points opposite the end faces 10 of the guide rolls so that the turbulence of the liquid can be greatly reduced in this way.

Fig. 7 illustrates a structure corresponding in all respects to that of Figs. 2 and 3 except that the floor portion 7" of the trough-shaped structure is downwardly curved at its opposite ends, as shown in Fig. 7, so as to produce a more laminar flow of the bath liquid in the region of the entrance and exit rolls.

Fig. 8 is a top plan view of a structure which also corresponds to that of Figs. 2 and 3, the structure of Fig. 8 being different in that the floor portion 7" of the trough-shaped structure is approximately $\frac{1}{3}$ of the length of the side plates 4 and is located adjacent to the discharge roll 2. In this way a great saving of the material of the trough-shaped structure is effected without causing any increase in the turbulence of the bath liquid at the portions of the filaments approaching the discharge roll 2, where turbulence is most undesirable.

All of the various embodiments of the trough-shaped structure may be mounted on the bath in the same way as illustrated in Fig. 3, and of course other supporting structures are possible without departing from the scope of the invention. The guide rolls shown in the various embodiments may be mounted on hangers 15 as schematically shown in Figs. 5 and 6 or any other supporting structure may be used for supporting the rolls. The arrows 6 in Fig. 3 illustrate how the treating liquid passing through the trough-shaped structure 4, 7 circulates about the trough-shaped structure from the discharge end of the bath to the entrance thereof.

It will be understood that each of the elements described above, or two or more together, may also find a useful application in other types of textile treating apparatus differing from the types described above.

While the invention has been illustrated and described as embodied in apparatus for preventing turbulence in a bath liquid for treating textile filaments, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; and a pair of opposite elongated plates supported by said side walls in spaced relation to each other, being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments.

2. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; a pair

of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between said plates and being connected thereto beneath the top edges thereof.

3. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between said plates and being connected to the bottom edges thereof.

4. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between said plates and being connected to the bottom edges thereof.

5. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; and a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments, each of said plates being formed with cutouts respectively located at opposite ends thereof and in which said rolls respectively extend.

6. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough, at least one of said guide rolls being formed with a pair of cutouts;

and a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending or spreading of the filaments, said plates respectively extending into said cutouts of said one guide roll.

7. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough, at least one of said guide rolls being formed with a pair of annular grooves spaced from each other; and a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending or spreading of the filaments, said plates respectively extending into said grooves of said one guide roll.

8. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between said plates and being connected to the bottom edges thereof, said floor member being located close to said guide rolls and extending beneath at least one of said guide rolls.

9. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between said plates and being connected to the bottom edges thereof, said floor member being located close to said guide rolls and having opposite end portions respectively curved downwardly away from said guide rolls.

10. Apparatus for treating textile filaments comprising, in combination, a tank for containing a liquid for treat-

ing textile filaments and having a bottom wall and side walls; a pair of spaced guide rolls within said tank having axes parallel to each other and to said bottom wall of said tank, one of said rolls being an entrance roll for guiding filaments into said bath and the other of said rolls being a discharge roll for guiding filaments out of said bath; a pair of opposite elongated plates carried by said side walls in spaced relation to each other and each extending from a point adjacent one of said rolls to a point adjacent the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between and being connected to bottom edges of said plates, said floor member being approximately $\frac{2}{3}$ the length of said plates and being located next to said discharge roll.

11. Apparatus for treating textile filaments, comprising, in combination, a tank for containing a liquid for treating textile filaments and having a bottom wall and side walls; a pair of spaced guide rolls within said tank having axes parallel to each other and to said bottom wall of said tank for guiding a group of filaments therethrough; a pair of opposite elongated plates carried by said side walls in spaced relation to each other and being located between said rolls along a path extending from one of said rolls to the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between said plates and being connected to the bottom edges thereof, said floor member being inclined with one end of said floor member located at a different elevation than an opposite end thereof.

12. Apparatus for treating textile filaments comprising, in combination, a tank for containing a liquid for treating textile filaments and having a bottom wall and side walls; a pair of spaced guide rolls within said tank having axes parallel to each other and to said bottom wall of said tank, one of said rolls being an entrance roll for guiding filaments into said bath and the other of said rolls being a discharge roll for guiding filaments out of said bath; a pair of opposite elongated plates carried by said side walls in spaced relation to each other and each extending from a point adjacent one of said rolls to a point adjacent the other of said rolls, being substantially normal to said bottom wall and having a top edge and a bottom edge, the latter being nearer to said bottom wall than said guide rolls, said plates adapted to prevent a turbulence in the liquid between said plates when a group of filaments are guided between said plates and to thereby prevent bending and spreading of the filaments; and a floor member extending between and being connected to bottom edges of said plate, said floor member having one end located adjacent to said entrance roll and an opposite end located adjacent to said discharge roll and said floor member being inclined with said one end thereof located at a greater distance from said entrance roll than the distance between said opposite end thereof and said discharge roll.
